UNITED STATES PATENT OFFICE.

ALBERT ABBE GRISWOLD, OF PROVIDENCE, RHODE ISLAND, AND ALVIN CARROLL GODDARD, OF RICHMOND HILL, NEW YORK; SAID GODDARD ASSIGNOR, BY MESNE ASSIGNMENTS, TO JOHN FRANCIS CHEVALIER, OF BROOKLINE, MASSACHUSETTS.

WIRE-FEED MECHANISM.

Original application filed May 17, 1922, Serial No. 560,481. Divided and this application filed March 10, 1924. Serial No. 698,132.

Our present application is a divisional application divided from our United States patent application, filed May 17, 1922, Serial No. 560,481, flexible shingle wiring machine.

Our invention has reference to an improvement in manufacturing flexible shingles and more particularly to an improvement in a wire feeding mechanism as applied to a machine for inserting a fastening wire into a flexible shingle thereby forming on a flexible shingle means for holding down the otherwise free end of the shingle, such means being the same as shown in United States Patent No. 1,274,410, granted August 6, 1918 to Albert Abbe Griswold, one of the present joint inventors.

The object of our invention is to improve the construction of a flexible shingle wiring machine, whereby on depression of a foot treadle the machine will feed a predetermined length of wire into the machine and simultaneously straighten the wire.

Our invention consists in the peculiar and novel construction of a flexible shingle wiring machine and more particularly to an improvement in the wire feed and straightening mechanism of a flexible shingle wiring machine; said wire feed and straightening mechanism having details of construction, as will be more fully set forth herein-after and claimed.

Figure 1 is a front view of the greater portion of our improved flexible shingle wiring machine.

Figure 2 is a top plan view of the machine.

Figure 3 is a side view looking at the right-hand side or wire feed side of the machine.

Figure 4 is an enlarged detail vertical sectional view through the wire feed and straightening mechanism, and

Figure 5 is a still further enlarged detail sectional view of that part of the wire feed mechanism that grips and feeds the wire into the machine.

In the drawings A indicates the frame, B the driving mechanism, C the wire feed mechanism and D a wire.

The frame A may be constructed as shown or any form adapted to support the operative mechanism.

The driving mechanism B, consists of a

driving shaft 1 supported in suitable bearings in the frame A. On the driving shaft 55 1 is a loose pulley 2 having one half of a clutch 3. The other half of the clutch 3 is splined to the driving shaft 1. A foot treadle 4 is pivotally secured to the frame A and through connecting rods 5, 5, and spring 60 6 is operatively connected to a clutch operating mechanism which in turn operates the half of the clutch 3 which is splined to the driving shaft 1. The clutch operating mechanism is a Standard V. & O. Press 65 Co., one stroke clutch mechanism and no claim is made to this clutch operating mechanism. A depression of the foot treadle 4, will through the clutch operating mechanism allow the driving mechanism B to operate 70 so that the machine will make one complete operation and stop, for each operation of the foot treadle.

The wire feed mechanism C consists of a crank 8 on the driving shaft 1 operatively 75 connected with a horizontal bar 9 which in turn is operatively connected to a vertical lever 10 on the rear end of a shaft 11 in bearings 12, 12, in a bracket 13, on the frame A. On the forward end of the shaft 80 11 is a vertical lever 14 operatively connected at its lower end to a slide 15 sliding in ways on a horizontal extension 16 of the frame A. The slide 15 has a spring operated arm 17 pivotally connected to a lever 85 18 on a wire gripping member 19, which has a wire gripping jaw 20 and which is pivotally secured to vertical arms on the slide 15, as shown in Figure 5. The wire 90 is gripped between the wire gripping jaw 20 and the top of the slide 15, to feed the wire D into the machine. On the frame extension 16 to the right of the slide 15 is a block 21 and a spring operated wire gripping jaw 22 which allows a free inward 95 movement of the wire D and also prevents a retrograde movement of the wire D. To the right of the block 21 and rotatably supported in bearings on the frame extension 100 16 is a series of wire straightening rolls 23, 23. On the end of the extension 16 is pivotally secured a normally horizontal wire tension and guide arm 24 having a bent inner stop end 25 and a bifurcated outer end 26 in which is pivotally secured a grooved 105 pulley 27. The wire D comes from a source

of supply, not shown, under the pulley 27, through the straightening rolls 23, 23, under the wire gripping jaws 22 and 20 and then through a hardened steel bushing in 5 the frame A.

The hardened steel bushing referred to forms part of a wire cutting device and has nothing to do with our present invention.

The wire D may be of any required size or 10 shape. It is preferably flat in cross section.

In the operation of the flexible shingle wiring machine having my improved wire feed mechanism, the first downward movement of the foot treadle 4, by the foot of the 15 operator, the driving mechanism B is brought into operation to close the clutch members on the driving shaft 1 and the pulley 2. The driving shaft 1 now makes one complete revolution and then stops. 20 In this first revolution of the driving shaft 1 the wire feed mechanism C feeds a predetermined length of the wire D into the machine.

The operation of my improved wire feed 25 mechanism C is as follows. In each revolution of the driving shaft 1 the crank 8 through the horizontal bar 9, the vertical lever 10, the shaft 11, the vertical lever 14, the slide 15, the arm 17, the lever 18, the 30 wire gripping member 19 and wire gripping jaw 20, operates the slide 15 to draw the slide towards the machine. In this movement of the slide 15 the wire D is gripped between the slide 15 and the gripping jaw 20, as shown in Figure 5, and the wire D is fed into the machine the required length for each revolution of the driving shaft 1. As the wire D is intermittently fed into the machine from a source of supply, not shown, it comes under the grooved pulley 27 then between the straightening rolls 23, 23, which straightens the wire and the wire then goes between the block 21 and the spring operated wire gripping jaw 22. 45 This wire gripping jaw is shaped so as to allow a free passage of the wire into the machine. When the inward movement of the wire stops, the wire gripping jaw 22 automatically grips the wire between the 50 wire gripping jaw 22 and the top of the block 21, which is fast to the frame extension 16, and prevents a retrograde movement of the wire.

Having thus described our invention we 55 claim as new:—

1. In a wire feed mechanism for a flexible shingle wiring machine, means for preventing a retrograde movement of the wire comprising a fixed block over which the wire 60 goes, vertical arms on the block a vertical

lever pivotally secured to the arms, a wire gripping jaw on the vertical lever and adapted to grip the wire between the jaw and the block, a projecting member on the block, and a spring operatively connected 65 with the projecting member and with the vertical lever.

2. In a wire feed mechanism for a flexible shingle wiring machine, a frame extension adapted to be fixed to the machine frame, 70 said frame extension forming a stop, a normally horizontal arm pivotally secured in the frame extension, said arm having a bent inner end under the frame extension and an outer bifurcated end, a grooved pulley rotatably secured in the bifurcated end and adapted to guide a wire under the pulley and means for pivotally securing the arm in the frame extension, the bottom of 75 which limits the downward movement of the arm.

3. In a wire feed mechanism for a flexible shingle wiring machine, a frame extension fixed to the machine frame, a slide slidably 85 mounted on the frame extension and having vertical arms, a recess in the slide, a spring element in the recess, an arm operatively connected with the spring element, a wire gripping member pivotally secured to the slide arms and having a wire gripping jaw 90 and an arm pivotally secured to the spring operated arm operatively connected to the spring element in the slide, a vertical lever pivotally secured to the slide and to a bracket on the frame and means for operatively connecting the vertical lever to the 95 driving mechanism of the machine.

4. In a wire feed mechanism for a flexible shingle wiring machine, the combination of 100 the following instrumentalities, a horizontal frame extension 16, a slide 15 on the frame extension and having a spring operated wire gripping member 19, a vertical lever 14 pivotally secured to the slide and pivotally 105 secured to a bracket on the machine frame, a block 21 on the frame extension and having a spring operated wire gripping jaw 22, a series of wire straightening rolls on the frame extension said frame extension having a bottom which forms a stop, a normally 110 horizontal arm 24 pivotally secured to the frame extension and having a bent inner end 25 under the frame extension and a bifurcated end 26 and a grooved pulley 27 rotatably secured in the bifurcated end 26, 115 all for the purpose as described.

In testimony whereof, we have signed our names to this specification.

ALBERT ABBE GRISWOLD.

ALVIN CARROLL GODDARD.
